United States Patent Office.

O. J. EVERSON, OF LAKE CITY, MINNESOTA.

Letters Patent No. 77,967, dated May 19, 1868.

IMPROVEMENT IN FENCES.

The Schedule referred to in these Letters Patent and making part of the same.

TO ALL WHOM IT MAY CONCERN:

Be it known that I, O. J. EVERSON, of Lake City, in the county of Wabashaw, and in the State of Minnesota, have invented certain new and useful Improvements in Fences; and do hereby declare that the following is a full, clear, and exact description thereof, reference being had to the accompanying drawings, and to the letters of reference marked thereon.

In the annexed drawings, making part of this specification, A A represent the stiles, and B B the end rails of the panels of a portable fence. These panels are placed together so that the end rails of the contiguous panels will rest against each other at their upper ends, but will stand apart at their lower ends, and bracing each other, as is represented in the drawings.

Each end rail is provided with a hole near its upper end, and each two contiguous ones are connected and fastened together by means of a pin or pivot driven through the holes in their upper ends, as seen at e.

C represents a stay-brace, which is made fast to one of the end rails by means of nails or screws, and which passes through a mortise in the other contiguous end rail.

The brace is provided with a series of holes, and the rail through which it passes is also provided with a hole crosswise of its mortise, through which a pin, a, passes, to confine the stay in the mortise.

By means of this stay, with its holes, and the mortise in the end rail, the two end rails, and consequently the panels, may be set at any suitable or desirable angle, and there held fast.

This fence may be readily taken to pieces for transportation, by removing the pin at e, and taking off the stay-brace C.

Having thus fully described my invention, what I claim as new, and desire to secure by Letters Patent, is—

Connecting and adjusting the panels of a portable fence together, by means of the pins and the stay-brace C, constructed and used with the panels, in the manner and for the purpose set forth.

In testimony that I claim the foregoing, I have hereunto set my hand, this 4th day of March, 1868.

O. J. EVERSON.
